CIGARETTE SLEEVE

Rudolph J. Vrana, Blauvelt, N. Y.

Application April 13, 1954, Serial No. 422,834

1 Claim. (Cl. 131—174)

This invention relates to new and useful improvements in smoking devices.

More particularly, the present invention proposes the construction of an improved cigarette shield which will cover the lighted end of a cigarette, which will prevent dropping of ashes, and will also be usable as a holder so as to prevent discoloration of a smoker's hands by nicotine from the cigarette.

As a further object, the present invention proposes forming the shield of fiberglass material in tubular shape with a conical inwardly extended end wall, the shield having inlet apertures to admit air to the burning end of a cigarette.

Still another object of the invention proposes forming the shield with an inner perforated tube and with a concentric outer holding tube coacting to define an insulating air space between the inner and outer tubes, thus to prevent said shield from becoming excessively warm to the touch.

In the accompanying drawings forming a material part of this disclosure:

Fig. 1 is a perspective view of a cigarette to which has been applied a shield constructed and arranged in accordance with the present invention.

Fig. 2 is an enlarged, longitudinal sectional view of the shield shown in Fig. 1, per se.

Fig. 3 is a view similar to Fig. 2 but showing a lighted cigarette in the shield.

Fig. 4 is a slide elevational view illustrating a modification of the present invention.

Fig. 5 is a longitudinal sectional view of the structure shown in Fig. 4.

Fig. 6 is a view similar to Fig. 5 but illustrating another modification of the invention.

Fig. 7 is a view similar to Fig. 2 but illustrating another modification of the invention.

Fig. 8 is a view similar to Figs. 2 and 7 but illustrating a still further modification of the invention.

Fig. 9 is an enlarged end elevational view of the form of Fig. 7, as seen from line 9—9 of Fig. 7.

The cigarette shield, in accordance with the first form of the invention illustrated in Figs. 1, 2 and 3, is in the form of a non-inflammable tubular sleeve 15.

Sleeve 15 preferably is made of a firm, inexpensive, and readily disposable material such as, for example, fiberglass or asbestos paper. The tube or sleeve 15 has an end portion 16 formed open so as to slip over the lighted end 17 of a cigarette 18 and frictionally and slidably engage the unburned portion thereof.

Sleeve 15 has at its other end a conical, inwardly directed end wall 19. This end wall 19 is imperforate, but the shield side wall adjacent thereto contains a plurality of air inlet openings 20 to admit air to the burning end 17 of cigarette 18 to support combustion.

The sleeve 15 is moved along the unburned portion of cigarette 18 as the cigarette is smoked and the sleeve

provides a convenient means to hold the cigarette without getting nicotine stain on the smoker's fingers.

The air passing openings 20 in the side wall of sleeve 15 may conveniently be formed by fashioning the shield 5 side wall of wide mesh fiberglass material.

The modification of the invention illustrated in Figs. 4 and 5 is characterized by the provision of a sleeve 24 made of similar material as sleeve 15 described above and having one portion 25 and an end wall 26 similar 10 to end portion 16 and end wall 19 of the sleeve 15. In addition, however, sleeve 24 contains a mouthpiece portion 27 which extends from its end portion 16 and is joined thereto by a section 28 weakened by a circumferential series of perforations 29. In this manner, the sleeve 24 is perforated for easy severance by the user of the mouthpiece portion 27 from the sleeve. The side wall of sleeve 24 contains air passing openings 30 adjacent end wall 26.

In Fig. 6, the modification of the invention illustrated 20 is similar to that shown in Figs. 4 and 5 and like parts are given like reference numerals but those in Fig. 6 are primed to distinguish the figures. In addition, a filter 31 is either permanently or removably engaged in the outer end of mouthpiece portion 27' of sleeve 24'. 25 Filter 31 may be one of any number of well known filters including cork, but preferably is made of crimped rolled filter paper.

The modification of the present invention illustrated in Fig. 7 is characterized by the provision of a shield 32 30 having an inner tubular sleeve 33 and an outer tubular sleeve 34 with an air space 35 between the sleeves. In this way, a double-walled formation results that insulates the cigarette to permit the shield to be held without discomfort.

Shield 32 has an inner end portion 36 with a tapering mouth 37 to slip over the lighted end of a cigarette. The bore 38 of this inner end portion 36 frictionally and slidably engages the unburned portion of a cigarette.

Inner sleeve 33 and outer sleeve 34 are connected together, preferably integrally, at the inner end portion 36 adjacent the mouth 37. Outer sleeve 34 is spaced from and concentrically disposed around the inner sleeve 33.

The outer end portion 39 of the inner sleeve 33 and 45 most of the length of the inner sleeve are provided with a plurality of spaced air inlet openings 44. The inner and outer sleeves are also joined together at the outer end 41 of the shield and are provided with a circumferential series of air inlet openings 42 extending through 50 the connection to the air passage or space 35 between the sleeves.

Inner sleeve 33 has an imperforate, conically shaped tip or end wall 43.

In this manner, the shield 32 is insulated by air space 55 so that it can be safely and comfortably held along its full length. Yet, ample air will be supplied to the burning end of a cigarette in a way to assure continual combustion so that the cigarette will not be extinguished. At the same time, the inner sleeve 33 and integral end plate 44 60 will assure that no hot ashes will fall or fly from the cigarette onto clothing or other combustible material.

The modification of the invention illustrated in Fig. 8 is characterized by the provision of a shield or tube 45 in the form of a thick tube of fiberglass or asbestos paper with 65 numerous air spaces between the strands of fiberglass or asbestos. Tube 45 has an inner end 46 with a tapered mouth 47 engageable with the lighted end of a cigarette, said mouth opening into a bore 48 in which is engaged the unburned portion of the cigarette.

Tube 45 also has an outer end 49 and a perforated, inwardly conical end wall 50 extending across the bore 48.

In all forms of the invention, the device is so designed as to safely enclose the lighted cigarette tip. At the same time, the ashes are prevented from dropping. Still further, when the cigarette is to be put out, the inwardly conical end wall is shifted into the lighted tip to be used as a snuffer. The entire device, of course, can be disposed of with the cigarette, due to its inexpensive construction.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A shield for the lighted end of a cigarette comprising a cylindrical body portion having outer and inner sleeve members, said inner sleeve member continuing at one end into an outwardly flaring portion in the body portion opening outwardly thereof, said outer sleeve being spaced from said inner sleeve member providing a space therebetween, and a perforated wall joining said sleeve members at the other end of the inner sleeve member, said

inner sleeve member being provided with a plurality of openings in its side wall communicating with the space between the sleeve members, the wall joining said sleeve members having openings communicating with the atmosphere, said inner sleeve member having a closure wall at one end formed with an inwardly conical portion extending axially of said inner sleeve member.
